W. M. Drell.

INVENTOR,
Thomas W. Carney,

BY *John Steeward.*
ATTORNEY.

UNITED STATES PATENT OFFICE.

THOMAS W. CARNEY, OF CLIFTON, NEW JERSEY.

SPLASH-BOARD FOR SINKS.

1,221,137.

Specification of Letters Patent. Patented Apr. 3, 1917.

Application filed February 10, 1917. Serial No. 147,807.

To all whom it may concern:

Be it known that I, THOMAS W. CARNEY, a citizen of the United States, residing at Clifton, in the county of Passaic and State of New Jersey, have invented certain new and useful Improvements in Splash-Boards for Sinks, of which the following is a specification.

The object of this invention is to provide a sink with means to prevent splashings of water from falling outward onto the clothing of a person standing in front of the sink, as in washing dishes and the like, such means being constructed so as efficiently to perform its principal function, thus indicated, and also so that when not in use it may be shifted to such position as to be wholly out of the way. My invention may be applied to tubs, bath-tubs and the like, 20 the term "sink" as herein used comprehending all such vessels or receptacles.

In the accompanying drawing,

Figure 1 is a perspective view of my splash-board attached to a sink;

Fig. 2 is a vertical sectional view of the sink and splash-board; and,

Fig. 3 is a perspective view of the splash-board, detached.

The sink *a* shown has a marginal flange *b* projecting outwardly, as is common in a well-known type of sinks. It is supported by being attached at the back to the wall and by the legs *c* at the front.

For supporting the splash-board, I may attach to the legs *c* the brackets *d* which reach up outward of the front wall of the sink under its flange *b*. The splash-board is pivoted to the upper ends of these brackets so as to hang pendent therefrom but be capable of being swung outwardly and upwardly to an upstanding position.

The splash-board is preferably formed of a piece of sheet metal *e* of substantially oblong shape and having at each of the corners formed by one long side and the two short sides of the piece an ear *f* which is bent into perpendicular relation to the plane of the body of the sheet, both such ears projecting in the same direction from the body 50 of the sheet.

Slits *g* are cut into the sheet from the aforesaid long side thereof, whereupon the intervening portion *h* of the sheet is bent outwardly from the body thereof (to wit

in the same direction as the ears *f*) in reverse curves *h' h''* (Fig. 2).

The ears *f* and the ends of the brackets are provided with suitable holes, and through these are passed the bolts *i* which afford a horizontal axis on which the splash-board is pivotally movable with reference to the sink.

The splash-board when not in use hangs pendent as shown in Fig. 1, and in such position imparts a finish to the front of the sink. When the splash-board is to be used to confine the splashings of water, it is swung up to the position shown by dotted lines in Fig. 2, where its upward pivotal movement is limited by contact of the splash-board with the flange *b* of the sink. In this position, the splashings which are thrown onto the splash-board and run down thereon will be diverted by the lip *h* (which it will be noted closes the opening which would otherwise exist between the splash-board and the sink flange) into the sink.

In order to afford a certain amount of friction to the pivotal movement of the splash-board, thus to keep it from falling from the upstanding position if accidentally moved, I provide spring washers *j* on the bolts *i*, the same maintaining a certain pressure upon the ears *f* and brackets *d* when the bolts, by screwing up their nuts, are clamped up tight.

It is preferred that the splash-board be enameled or otherwise treated so as to conform with the finish of the sink.

Having thus fully described my invention, what I claim as new and desire to secure by Letters Patent is:—

1. In combination, a sink structure and a splash-board pivoted thereto on a horizontal axis outward of one upright wall of said structure, said splash-board having limited pivotal movement from a position where it hangs pendent relatively to said axis to a position where it upstands therefrom.

2. In combination, a sink structure and a splash-board pivoted thereto on a horizontal axis outward of one upright wall of said structure, said splash-board having limited pivotal movement from a position where it hangs pendent relatively to said axis to a position where it upstands therefrom and having a lip projecting outwardly

in the pendent position of the splash-board and adapted to overhang the margin of said wall in the upstanding position of said splash-board.

3. In combination, a sink structure and a splash-board pivoted thereto on a horizontal axis outward of one upright wall of said structure, said splash-board having limited pivotal movement from a position 10 where it hangs pendent relatively to said axis to a position where it upstands therefrom and consisting of a piece of sheet material having the edge portion thereof which in pivotal movement of the splash-board remains always nearest said wall bent out-

wardly and thereby adapted to overhang said wall in the upstanding position of the splash-board.

4. In combination, a sink structure having a marginal outward flange on one upright wall thereof and a splash-board pivoted to said structure on a horizontal axis beneath the flange and hanging pendent, the pivotal part of said splash-board projecting forwardly, whereby the splash-board 20 may be swung outwardly and upwardly and come to rest against the sink structure in an upstanding position. 25

In testimony whereof I affix my signature.

THOMAS W. CARNEY.
